UNITED STATES PATENT OFFICE.

JOSEPH A. HARRINGTON, OF CHESTER, PENNSYLVANIA, ASSIGNOR OF ONE-HALF TO
MICHAEL J. LYDON, OF BOSTON, MASSACHUSETTS.

SHARPENING DEVICE FOR SAFETY-RAZOR BLADES.

Application filed June 23, 1920, Serial No. 891,081.

To all whom it may concern:

Be it known that I, JOSEPH A. HARRINGTON, a citizen of the United States, residing at Chester, in the county of Delaware and State of Pennsylvania, have invented new and useful Improvements in Sharpening Devices for Safety-Razor Blades, of which the following is a specification.

This invention relates to sharpening devices for safety razor blades.

The object of the invention is to provide a simple effective device by means of which a safety razor blade may be sharpened by rotating a suitable manually operated actuating unit alternately in opposite directions and by such rotation the blade may be presented to the sharpening surface or surfaces first on one face and then on the other, the direction of rotation of the sharpening drums being changed automatically with the reversal of the blade.

Another object of the invention is to provide a convenient means for holding the blade during the sharpening operation.

The invention consists in the combination and arrangement of parts set forth in the following specification and particularly as pointed out in the claims thereof.

Referring to the drawings:

Figure 1 is an end elevation of a sharpening device embodying my invention.

Fig. 2 is an elevation of the opposite end of the sharpening device from that illustrated in Figure 1, the same being partially broken away and illustrated in section.

Fig. 3 is a vertical sectional elevation taken on the line 3—3 of Figure 1.

Fig. 4 is a horizontal sectional elevation taken on the line 4—4, Figure 1.

Fig. 5 is a transverse section taken on the line 5—5, Fig. 3.

Fig. 6 is a detailed view of the plate holder with the razor blade illustrated therein.

Fig. 7 is a detailed view of the razor blade holder similar to Fig. 6 but with the upper portion of said holder removed.

Like numerals refer to like parts throughout the several views of the drawings.

In the drawings, 1 represents a casing embodying a cylindrical wall 2 and walls 3 and 4 which are located a sufficient distance from each end of the cylindrical wall 2 to form recesses 5 and 6 at the opposite ends of the casing, while a compartment 7 is provided upon the interior thereof. Mounted to rotate

in the walls 3 and 4 are a pair of sharpening drums 8 and 9 each identical in construction and embodying a tube 10 having sleeves 11 and 12 securely fastened within the opposite ends. The sleeve 11 is mounted to rotate in a bearing 13 in the wall 3, while at the opposite end of the roll the tube 10 rotates in a bearing 14 in the wall 4. A spool 15 preferably constructed of wood is mounted upon the tube 10 being securely fastened thereto. The periphery of the sharpening drums 8 and 9 are composed of a plurality of strips 16 and 17 of suitable material, such as leather or the like, which extend around the spool 15 in the form of a helix. The strip 16 is preferably more resilient than the strip 17 and is provided with an abrasive surface which is adapted to grind the razor blade, while the strip 17 has a surface similar to a strop.

Also mounted in bearings 18 and 19 in the walls 3 and 4 and located upon the median axial line of the casing 1 is a rocking member 20 which embodies a sleeve 21 having a flange 22 and provided with a slot 23 into which projects the ends of a pair of oppositely disposed members 24 which are pressed from sheet metal and have a semi-cylindrical portion 25 and flanges 26, it being a portion of said flanges which projects into the slot 23 of the sleeve 21. A narrow space 27 separates the opposite faces of the adjacent flanges 26 and into the open end of the rocking member 20 a blade holder 28 is inserted to hold a razor blade 29, the said blade extending through the space 27 between the opposite faces of the flanges 26.

The blade holder 28 is formed of two oppositely disposed semi-cylindrical members 30 and 31, the member 30 having a collar 32 rigidly fastened thereto at the upper end thereof and a blade positioning member 33 located therein provided with a pair of projections 34 adapted to project through openings 35 in the blade 29, thereby correctly positioning the blade in the holder. The member 31 extends through the collar 32 and is provided with a flange 36 formed integral therewith adapted to be engaged by the thumb or fingers in order to remove the member 31 when it is desired to place a blade in the holder.

A slot 37 is provided in the wall 3, the said slot intersecting the opening through which the rocking member 20 extends and

which constitutes the bearing 18, the said slot being of sufficient length to allow the insertion of the blade 29 therethrough.

To operate the rocking member 20 with 5 the blade holder 28 therein together with the sharpening drums 8, a manually operable actuating unit 38 is provided located within the recess 6 consisting of an internal gear 39 which may be fastened in any suitable manner to a disk 40 and rotated in unison therewith through the medium of a handle 41. The actuating unit 38 is retained in the recess 6 by means of an inwardly turned annular flange 42 provided upon the 10 cylindrical member 2. A spring 43 is securely fastened to the disk 40 and is bent inwardly to engage and apply sufficient pressure to the inner surface of the flange 22 to cause the rocking member 20 to move in unison therewith, thereby forming a slipping friction driving connection between the rotary actuating unit 38 and the rocking member 20. A washer 44 surrounds the sleeve 21 between the wall 4 and the spring 43 to 15 prevent undue friction between the actuating unit and the wall 4. The internal gear 39 meshes with a pair of spur gears 46 which are fastened to the sleeves 12, thereby forming a positive driving connection between the rotary actuating unit 38 and the 20 sharpening drums 8.

If it is so desired a projection 47 may be provided upon the member 31 which when said member is located in the position illustrated in Fig. 3, springs into a recess 48 formed in the adjacent member 24 and when the blade holder is removed from the rocking member and it is desired to remove the blade holder therefrom without entirely 25 withdrawing the member 31 from the collar 32, the said member 31 may be moved to a position where the projection 47 will spring into a recess 49 formed in the collar 32, thereby preventing the said member 31 from 30 becoming disengaged from the collar.

Another cylindrical casing 50 may be provided to surround and closely fit the cylindrical member 2 of the casing 1, if it is desired, thereby increasing the strength of the 35 casing 1 and adding to the general appearance of the same.

The general operation of the sharpening device hereinbefore described is as follows: The blade holder 28 is first removed from 40 the rocking member 20 and the member 31 then moved longitudinally within the collar 32 until the projection 47 upon said member springs into the recess 49 of said collar. A razor blade 29 is then placed in position 45 upon the blade holder with the projections 34 projecting through the openings 35 in the razor blade and the member 31 is again pushed to its rearward position. The blade holder with the blade therein is then again 50 placed in position in the rocking member 20.

The handle 41 is then rotated alternately in opposite directions preferably several rotations in each direction.

Assuming that at the start the blade 29 occupies the position illustrated in full lines 55 in Fig. 5, and the handle 41 is rotated clockwise in Figs. 2 and 5, it will be evident that the drums 8 and 9 will be positively operated by reason of the gearing connected with the rotary actuating unit 38, while at the same 60 time the spring 45, positively driven by the actuating unit 38, engages the flange 22 of the rocking member 20 and a slipping driving connection takes place between said spring and said rocking member. The frictional driving connection between the spring 45 and rocking member 20 forms a means 65 for furnishing a desired pressure of the blade against the sharpening drums.

If, now, after several turns of the handle 70 in a clockwise direction, the direction of the handle be reversed, it will be evident that the position of the blade 29 will be reversed since the blade will move freely across the intervening space between the drums until the blade occupies the position shown in dotted lines, Fig. 5, whereupon the blade encountering the drums ceases to rotate, is held with the proper pressure against the drums and the drums are then rotated in 75 an opposite direction, or, in other words, in a counterclockwise direction. The operator continues to rotate the handle alternately in opposite directions until the blade has been sufficiently sharpened, the strip 16 80 performing the grinding operation, while the strip 17 acts to finish or smooth the edge of the blade and perform a stropping operation. After the blade has been sufficiently sharpened, it may be removed from its 85 holder as previously described.

I claim:

1. A sharpening device for razor blades having, in combination, a casing comprising a cylindrical wall, end walls dividing said casing into a central compartment with a recess at opposite ends of said casing, a pair of rotary sharpening drums mounted in said end walls, a rocking member mounted upon said end walls between said drums and adapted to have a razor blade mounted therein, said rocking member embodying therein a sleeve located at one end thereof, a rotary actuating unit embodying therein an internal gear and a disc located in one of said recesses, said actuating unit also embodying therein a spring fast to said disc and adapted to force said sleeve against said disc thereby forming a slipping driving connection between said actuating unit and said rocking member and gears forming a positive driving connection between said internal gear and said sharpening drums.

2. A sharpening device for razor blades having, in combination, a casing comprising

ing a cylindrical wall, end walls dividing said casing into a central compartment with a recess at opposite ends of said casing, a pair of rotary sharpening drums mounted 5 in said end walls, a rocking member mounted upon said end walls between said drums adapted to have a blade inserted therein from one end thereof to rock in unison therewith to present the edges of said blade into 10 contact with said drums, a rotary actuating unit embodying therein an internal gear and a disc fast to said gear mounted in one of the recesses at the end of said casing, said actuating unit also embodying therein a 15 spring fast to said disc and positively ro-

tated thereby adapted to form a slipping driving connection between said unit and said rocking member, and gears forming a positive driving connection between said internal gear and said drums, said casing being provided with an annular flange formed integral therewith adapted to hold said unit in said recess. 20

In testimony whereof I have hereunto set my hand in presence of two subscribing 25 witnesses.

JOSEPH A. HARRINGTON.
